UNITED STATES PATENT OFFICE

WALLACE D. JOHNSON, OF BELOIT, WISCONSIN, ASSIGNOR TO YATES-AMERICAN MACHINE COMPANY, OF BELOIT, WISCONSIN, A CORPORATION OF DELAWARE

CHIP BREAKER

Application filed December 15, 1928. Serial No. 326,361.

The present invention pertains to wood working machines, and has to do particularly with the chip breakers used in association with the cutter heads in such machines.

When the ordinary chip breaker is struck and pushed back by the in-end of a board traveling at a high rate of speed, the chip breaker momentarily leaves the board, and it frequently happens that the in-end of the board reaches the cutter head and is drawn into the same before the chip breaker returns to force the board back against the opposite guide, with the result that the in-end of the board is cut unevenly or sniped.

The principal object of the invention is to provide an improved chip breaker which will prevent the in-end of the board from being sniped.

Another important object is to provide an improved chip breaker which will reduce to a minimum the pressure exerted by the same against the side of the board.

A further object is to provide an improved chip breaker which, when it is moved back by the board, does not change its position with respect to the board until after it has been moved back a certain distance.

Other objects and advantages of the invention will be evident to those skilled in the art upon a full understanding of the construction, arrangement and operation of the improved chip breaker.

One form of the invention is presented herein for the purpose of exemplification, but it will of course be appreciated that the invention is susceptible of embodiment in other structurally modified forms coming equally within the scope of the appended claims.

In the accompanying drawing:

Fig. 1 is a partially sectioned plan view of a chip breaker constructed in accordance with the invention; and

Fig. 2 is a side view of the chip breaker.

The chip breaker shown in the drawing is carried by the support 10 in which the cutter head (not shown) is mounted. It includes a curved arm 11 which extends about one side of the cutter head and is shaped to form a hood for the same. The board to be cut approaches the chip breaker in the direction of

the arrow 12 and engages with a shoe 13 which is carried by the arm 11. The arm 11 is pivoted at 14 to the support 10, and backward swinging movement of the free end of the arm carrying the shoe 13 is resisted by a resiliently yieldable spring device 15 having a pivoted coupling member 16 which hooks about a downwardly extending pin 17 on the arm and may be swung into or out of hooked position by a conveniently accessible handle 18.

The shoe 13 is pivotally attached at longitudinally spaced points 19 and 20 to a pair of parallel links 21 and 22 which are in turn pivotally attached at 23 and 24 to the arm 11, and backward movement of the shoe with respect to the arm is yieldingly resisted by means of a coil spring 25. The coil spring encircles a guide rod 26 and is compressed between a washer 27 on the rod which bears against the rear end of the shoe and another washer 28 on the rod which bears against a threaded sleeve 29 screwed into a threaded aperture 30 in the arm. The pressure of the coil spring on the shoe occurs in line with the direction of movement of the shoe.

The shoe 13 is much lighter than the arm 11 and the spring 25 offers considerably less resistance than the spring device 15, with the result that, when the shoe is struck and pushed back by the in-end of the board, it moves independently of the arm and does not commence to change its position with respect to the edge of the board until after its backward movement has continued to such an extent as to necessitate some movement of the arm, after which the shoe of course swings with the arm about the pivotal axis of the latter, as in an ordinary chip breaker.

The chip breaker of the invention possesses many advantages over the ordinary chip breaker. Not only does it effectively prevent sniping, but it is extremely quick in its action, does not bind, dance or chatter, produces a good edge on the stock, and does not tend to wedge against the stock or be drawn in and moved along by the same. While the chip breaker shown in the drawing is designed particularly for use with a side head, it may

also be used in association with a top head, and may, if desired, be of sectional construction.

I claim:

- 5 1. In a chip breaker, the combination with a cutter head, and a support for the same, of a hood for the cutter head pivotally attached to the support at one side of the cutter head, resiliently yieldable means for resisting movement of the hood about the pivotal axis thereof, a shoe carried by the hood at the opposite side of the cutter head from the pivotal axis of the hood, parallel links pivotally connected to the shoe and to the hood for allowing the shoe to shift bodily with respect to the hood, and a compressed spring operating against the shoe in line with the direction of movement thereof for resisting movement of the shoe relative to the hood.
- 10 15 2. In a chip breaker, the combination with a cutter head, and a support for the same, of an arm pivotally attached to the support at one side of the cutter head, resiliently yieldable means for resisting movement of the arm about the pivotal axis thereof, a shoe carried by the arm at the opposite side of the cutter head from the pivotal axis of the arm, parallel links pivotally connected to the shoe and to the arm for allowing the shoe to shift bodily with respect to the arm, and resiliently yieldable means for resisting movement of the shoe relative to the arm.
- 15 20 25 3. In a chip breaker, the combination with a cutter head, and a support for the same, of an arm pivotally attached to the support at one side of the cutter head, resiliently yieldable means for resisting movement of the arm about the pivotal axis thereof, a shoe carried by the arm at the opposite side of the cutter head from the pivotal axis of the arm, parallel links pivotally connected to the shoe and to the arm for allowing the shoe to shift bodily with respect to the arm, and resiliently yieldable means for resisting movement of the shoe relative to the arm, the pivotal connections between the shoe and the link being closer to the pivotal axis of the arm than the pivotal connections between the arm and the links.
- 25 30 35 40 45 50 55 60 65 4. In a chip breaker, the combination with a cutter head, and a support for the same, of an arm for the cutter head pivotally attached to the support at one side of the cutter head, a spring for resisting movement of the arm about the pivotal axis thereof, an elongated shoe carried by the arm and provided with a work-engaging plate at the opposite side of the cutter head from the pivotal axis of the arm, parallel links pivotally connected to the shoe and to the arm for allowing the shoe to shift bodily with respect to the arm, and a spring operating against the shoe at the point of connection of one of the links in a direction substantially tangential to the arc

of movement of such link for resisting movement of the shoe relative to the arm.

In witness whereof I have hereunto subscribed my name.

WALLACE D. JOHNSON.
